UNITED STATES PATENT OFFICE.

ADOLF SCHLAGETER AND JOSEPH KLEIN, OF CENTRAL CITY, ILLINOIS.

DESIGN FOR A PICK.

SPECIFICATION forming part of Design No. 30,408, dated March 28, 1899.

Application filed March 2, 1899. Serial No. 707,534. Term of patent 7 years.

To all whom it may concern:

Be it known that we, ADOLF SCHLAGETER and JOSEPH KLEIN, citizens of the United States, residing at Central City, in the county of Marion and State of Illinois, have invented and produced a new and original Design for Picks; and we do hereby declare the following to be a full, clear, and exact description of the same, reference being had to the accompanying drawing, forming a part thereof.

The drawing represents a perspective view of the pick.

The design relates to the configuration of the pick-head.

15 The leading features of the design appear in the following description:

A is the head proper, having its opposite sides slightly convex, with an opening B upon the outer face and tapered ears C upon the 20 opposite face, as shown. Centrally from one

end of the head extends the part D, which is tapered at its outer end. At the opposite end of the head is the cylindrical part E, terminating at a distance from the end of the head in the part F, which is broader than the head, 25 and its upper face is curved toward the outer end, as seen at G, the under side forming practically a right angle with the vertical side adjacent the end of the head.

What is claimed as new is—

30 The design for a pick substantially as herein shown and described.

In testimony whereof we affix our signatures in presence of two witnesses.

ADOLF SCHLAGETER.
JOSEPH KLEIN.
